[57] CLAIM

The ornamental design for a counter armchair, substantially as shown and described.

DESCRIPTION

FIG. 1 is a perspective view, looking from the front and side at about a 45° angle, of a counter armchair embodying my new design.

FIG. 2 is a perspective view thereof, looking from one side.

FIG. 3 is a perspective view thereof, looking down from above and from the rear at about 45°.

FIG. 4 is a perspective view thereof, looking from the rear and slightly above.

FIG. 5 is a bottom view thereof.

FIG. 6 is a perspective view, looking down from above and from one side and the front of a modified form of counter armchair also embodying my new design.

FIG. 7 is a perspective view of the counter armchair of FIG. 6, looking from the rear and one side and from above.

FIG. 8 is a perspective view, looking down from the front and one side of another modified form of counter armchair also embodying my new design.

FIG. 9 is a perspective view of the counter armchair of FIG. 8, looking down from the rear and one side.

FIG. 10 is a bottom view of the counter armchair of FIGS. 8 and 9.
